C. L. WECHT.
TOY WHEELBARROW.
APPLICATION FILED JAN. 3, 1920.

1,387,570.

Patented Aug. 16, 1921.

Inventor

Charles L. Wecht.

William W. Deane
his Attorney

UNITED STATES PATENT OFFICE.

CHARLES L. WECHT, OF LOGANSPORT, INDIANA.

TOY WHEELBARROW.

1,387,570.

Specification of Letters Patent. Patented Aug. 16, 1921.

Application filed January 3, 1920. Serial No. 349,336.

To all whom it may concern:

Be it known that I, CHARLES L. WECHT, a citizen of the United States, residing at Logansport, in the county of Cass and State 5 of Indiana, have invented certain new and useful Improvements in Toy Wheelbarrows, of which the following is a specification, reference being had therein to the accompanying drawing.

10 My invention relates to improvements in wheelbarrows, adapted for use as toys, but not restricted to this use as they may be constructed in full sizes for working purposes.

15 An important object of the invention is to provide means whereby the frame-work of the wheelbarrow may be constructed of a single section of metal, such as a wire, rod, or pipe, bent to produce the several desired 20 elements.

A further object of the invention is to provide a device of the above mentioned character, which is simple in construction, and inexpensive to manufacture.

25 Other objects and advantages of the invention will be apparent during the course of the following description.

In the accompanying drawings forming 30 a part of this specification, and in which like numerals are employed to designate like parts throughout the same,

Figure 1 is a perspective view of a wheelbarrow embodying my invention,

Fig. 2 is a similar view, showing the lower 35 portions of the wheelbarrow, and,

Fig. 3 is a transverse section taken on line 3-3 of Fig. 1.

In the drawings, wherein for the purpose 40 of illustration is shown a preferred embodiment of my invention, the numeral 5 designates the frame-work of the wheelbarrow, as a whole. This frame-work is formed from a single section of metal, such as a rod or wire, and bent between its ends, forming 45 longitudinal members 6. These longitudinal members cross each other at a point 7, and are preferably bound together by a staple 8. These members may be connected by being fused, bolted or riveted together. The forward extensions 6' of the longitudinal members 6 carry at their forward ends a transverse element or axle 9, formed by bending the rod or wire, as is obvious. The 50 longitudinal members 6 are bent at spaced

points 10, forming U-shaped legs 11. The 55 rear ends of the longitudinal members 6 serve as handles, and carry hand-grips 12, which might be omitted, if desired.

The numeral 13 designates a rolling element or wheel, preferably in the form of a 60 wooden cylinder, while any form of wheel may be employed. The wheel 13 is provided with a central opening for the reception of a sleeve or bushing 14, preferably formed of brass, and rotatable upon the axle 9. 65

The numeral 15 designates the floor or bottom of the body of the wheelbarrow, arranged upon the frame-work 5. The staple 8 engages the bottom 15, together with staples 16 and 17. The staples 17 are preferably arranged at or near the points 10 of bending. The body further comprises a forward end 18, preferably permanently secured to the bottom 15, and carrying guide rods 19. Sides 20 have their forward ends 75 adapted for insertion behind the rods 19, and are equipped with transverse bars 21, adapted for insertion within sockets 22. I wish it understood that the invention is not restricted to the particular form of body 80 shown and described, as it may be varied, if desired. The body of the wheelbarrow may be changed in form, shape, and material. The body or bottom portion 15 may be formed of metal instead of wood, in which 85 case the frame-work of the wheelbarrow may be bolted, riveted or fused thereto.

From the foregoing description it is thought that the invention should be readily 90 understood.

It is to be understood that the form of my invention herewith shown and described is to be taken as a preferred example of the same, and that various changes in the shape, size, and arrangement of parts, and the material of construction, and manner of connection, may be resorted to without departing from the spirit of my invention, or the scope of the subjoined claim.

Having thus described my invention, I 100 claim:—

A wheelbarrow including a frame formed of a single metal rod bent intermediate its ends to provide an axle and two side bars, the side-bars extending rearwardly from the 105 axle in parallel relationship to each other for a short distance, then crossing and diverging to the extremities of the rods, the

diverging portions of the side-bars being bent downwardly to form parallel U-shaped members, a wheel mounted on said axle, a body mounted on the frame, and fastening 5 means securing the crossed portions and the diverging portions of the side-bars to said body.

In testimony whereof I hereunto affix my signature in the presence of two witnesses.

CHARLES L. WECHT.
